US0D1106302S

(12) **United States Design Patent** (10) Patent No.: **US D1,106,302 S**
(45) Date of Patent: ** Dec. 16, 2025

(54) **TRANSFER ROBOT**

(71) Applicant: **KUKA ROBOTICS GUANGDONG CO., LTD.**, Foshan (CN)

(72) Inventors: **Liangsheng Zhou**, Foshan (CN); **Jiaxing Wang**, Foshan (CN); **Enjia Wu**, Foshan (CN)

(73) Assignee: **KUKA ROBOTICS GUANGDONG CO., LTD.**, Foshan (CN)

(**) Term: **15 Years**

(21) Appl. No.: **35/520,143**

(22) Filed: **Feb. 27, 2023**

(80) **Hague Agreement Data**

Int. Filing Date: **Feb. 27, 2023**

Int. Reg. No.: **DM/229283**

Int. Reg. Date: **Feb. 27, 2023**

Int. Reg. Pub. Date: **Mar. 1, 2024**

(30) **Foreign Application Priority Data**

Jan. 16, 2023 (CN) 202330027593.0

(51) **LOC (15) Cl.** **15-99**

(52) **U.S. Cl.**

USPC **D15/199**

(57) **CLAIM**

The ornamental design for a transfer robot as shown and described.

DESCRIPTION

Transfer Robot

Reproduction 1.1 is a front view of a transfer robot, showing our new design; reproduction 1.2 is a back view thereof; reproduction 1.3 is a left view thereof; reproduction 1.4 is a right view thereof; reproduction 1.5 is a top view thereof; reproduction 1.6 is a bottom view thereof; reproduction 1.7 is a perspective view thereof.

The lightened parts in each of the reproductions 1.1 to 1.7 shown within the broken-lines perimeter illustrate portions of the transfer robot that form no part of the claimed design.

1 Claim, 5 Drawing Sheets
